(57) **CLAIM**

The ornamental design for a pharmaceutical package, as shown and described.

DESCRIPTION

FIG. 1 is a top, left, front perspective view of a pharmaceutical package according to our design;

FIG. 2 is a top, left, rear perspective view thereof;

FIG. 3 is another top, left, rear perspective view thereof;

FIG. 4 is a top, right, front perspective view thereof;

FIG. 5 is a bottom, right, front perspective view thereof;

FIG. 6 is a bottom, left, rear perspective view thereof;

FIG. 7 is a top plan view thereof;

FIG. 8 is a bottom plan view thereof;

FIG. 9 is a right side elevation view thereof;

FIG. 10 is a left side elevation view thereof;

FIG. 11 is a front elevation view thereof; and,

FIG. 12 is a rear elevation view thereof.

The broken line portion in the drawings illustrates portions of the pharmaceutical package that form no part of the claimed design.
